United States Patent Office

Des. 195,466

Patented June 18, 1963

195,466

TEST SCORING MACHINE

Edwin S. Elste, 2240 Washington Ave., Silver Spring, Md.;
John F. Kellogg, 8301 Meadowlark Lane, Bethesda,
Md.; and John D. O'Neale, 510 S. Walter Reed Drive,
Bethesda, Md.

Filed Oct. 19, 1962, Ser. No. 72,198

Term of patent 14 years

(Cl. D26—5)

FIG. 1.

FIG. 2.

FIG. 3.FIG. 4.FIG. 5.FIGURE 1 is a right side perspective view of a test scoring machine, showing our new design;

FIGURE 2 is a right side elevational view thereof;

FIGURE 3 is a top plan view thereof;

FIGURE 4 is a back elevational view thereof; and,

FIGURE 5 is a front elevational view thereof.

The side not shown is identical to the side shown.

The bottom is substantially plain.

The essential features of the design reside in the portions shown in solid lines.

We claim:

The ornamental design for a test scoring machine, substantially as shown and described.
